(57) **CLAIM**

The ornamental design for a plumeria blossom jewelry, as shown and described.

DESCRIPTION

FIG. 1 is a perspective view showing my new design.

FIG. 2 is a front view thereof.

FIG. 3 is a rear view thereof.

FIG. 4 is a left view thereof.

FIG. 5 is a right view thereof.

FIG. 6 is a top view thereof.

FIG. 7 is a bottom view thereof.

FIG. 8 is a perspective view showing my new design for plumeria blossom jewelry as a ring.

FIG. 9 is a perspective view of my new design thereof as an adornment for a pendant.

FIG. 10 is a perspective view of my new design thereof as a necklace pendant.

FIG. 11 is a perspective view of my new design thereof as an earring; and,

FIG. 12 is a perspective view showing the plumeria blossom jewelry of my new design as an ornament for a bracelet, wherein no claim is claimed for the bracelet as shown, illustrating the overall appearance of the plumeria blossom jewelry of my new design.

The broken lines in FIGS. 8-12 are for illustrative purposes only and form no part of the claimed design.

1 Claim, 12 Drawing Sheets
